UNITED STATES PATENT OFFICE.

SWAN E. NORD, OF SEATTLE, WASHINGTON.

SELF-DRAINING OIL CAN.

Application filed September 18, 1926. Serial No. 136,326.

My invention has particular reference to improvements in the type of can commonly used by wholesalers of lubricating oil in making deliveries to the retail trade. The 5 practice is, to transport oil for this purpose in cans of a size which permits them to be conveniently handled. The standard can thus used has a capacity of five gallons, and is provided in its body portion with a plurality of circumferential corrugations designed to add rigidity thereto, but which obviously afford oil-retaining recesses interiorly of the can.

In making deliveries from these cans, I 15 have found, owing to the viscosity of the oil, said corrugations, and the time ordinarily allotted for pouring, that approximately three-fourths of a pint of oil is left in each can after the same is deemed to be empty, 20 with the result that the purchaser is deprived of a quantity of oil to which he is entitled, and apparently without the fault of the seller. As many thousands of these cans are thus emptied daily, the ultimate loss to purchasers is enormous.

The main object of my invention is, to practically eliminate this loss, and in furtherance of said object, I provide a can of this character, rigid in construction yet free of 30 said corrugations, having a bottom portion of a form which allows the residue of the oil to drain quickly into an auxiliary and special receptacle communicating therewith, and from whence it can be readily deposited into the container desired.

In the accompanying drawing—

Figure 1 is an elevation of the device complete, its lower portion being partly broken away, indicating a flared double bottom, the auxiliary oil receptacle, a swivel cap therefor, and means for retaining the cap to the can when the same is disconnected from the receptacle;

Fig. 2, a cross section, drawn on the line 45 2—2, of Fig. 1; and,

Fig. 3, a view, in detail, of a bottom section of the device, showing the cap removed from the receptacle and suspended from the lower bottom of the can, the parts indicated being 50 now in operative position for discharging any residue of oil therefrom.

In the preferred embodiment of the invention, the device comprises a cylindrical body portion 1, in which the corrugations referred 55 to have been dispensed with. The top sec-

tions of the can 2 and 3, the cover 4, and the handle 5, present the usual construction found in cans of this type. The lower bottom, designated as 6, is disposed somewhat above the base 7, so as to provide a housing 60 for parts heretofore referred to but which presently will be described with more particularity.

A double bottom 10, in the form of a hollow, truncated and inverted cone is fastened to the body of the can, its smaller end being disposed adjacent said bottom 6. An auxiliary oil receptacle extends through the bottom 6, is secured to said end of the bottom 10 and establishes communication for oil therewith. Said receptacle is provided with a cylindrical body portion 11, which terminates at one end in a flared section 12, affording a strong connecting element between the bottom 10 and the body of the receptacle, and 70 terminates at the other end in an exteriorly threaded section 13.

A cap 14 for the receptacle, adapted to threadedly engage the section 13 and having a leather washer 15 to make it oiltight, is provided with a circumferential groove 16, in which is rotatably mounted a ring 17, having an eye 18, carrying a chain 19. A member, having a flat body portion 20, terminating at one end in a hook 21, is secured to the bottom 6. It serves, through its fastening elements, to support one end of said chain and a keeper 22 for the hook, said keeper being made of spring material. The chain, as is evident, is for the purpose of retaining the cap to the can so it will not be misplaced, and the hook and keeper are designed to carry and retain the cap, through said eye, as shown in Fig. 3, when the cap is removed from the receptacle.

The utilization of the device is quite obvious. When the oil has been poured from the can in the usual manner and the can left standing on its base, the elimination of the corrugations mentioned and the oil-retaining recesses incident to a can having the ordinary horizontal bottom, and the provision of a smooth inner surface terminating in the flared bottom, will permit the residue of the oil to flow toward and be quickly collected in said receptacle and in the bottom 10 adjacent thereto. The can is then placed over a suitable container, the cap removed from the receptacle and hung on the hook, as shown in Fig. 3, when practically all of the oil remain-

ing in the can will be deposited in the container.

In delivering lubricating oil to retailers, often a number of these cans are emptied at 5 one delivery, and deliveries of other products are made, thus affording the short time necessary for the residue of the oil to collect and be transferred as just described. If desired, however, immediately after the contents are 10 poured from the can the cap can be removed and the residue of the oil allowed to drip directly into said container.

Under the present construction, the bottom 10, in addition to the function already described, 15 serves to add rigidity to the body of the can, and the fact that the bottom 6 affords support for the bottom 10, also increases the stability of the structure. I contemplate that, preferably, this can shall have a capacity for oil the same as the standard cans here- 20 tofore mentioned.

While I have shown one embodiment of the invention, I may, however, provide other arrangements and constructions for carrying 25 out the same without departing from the spirit or scope of the invention as defined by the appended claims.

I claim:

1. A self-draining oil can, comprising a 30 container, a horizontal bottom member disposed above the base of the container, a central opening in said member, a second bottom member, disposed above the first-named member, in the form of a hollow, truncated and 35 inverted cone, its smaller end axially aligned with said opening, an auxiliary receptacle for oil extending through said opening and secured to said end of the second-named member, and an oil-tight cap threadedly engaged 40 with the free end of the receptacle.

2. A self-draining oil can, comprising a container, a horizontal bottom member therefor, a double bottom secured within the container, converging downwardly to an outlet, an auxiliary receptacle for oil extending 45 through the member, one end secured to the outlet and adapted to establish communication for oil therebetween, its other end, free and open, extending below the member, a detachable cap for the free and open end, a second member secured to the first member and exteriorly thereof, carrying at one end a hook, provided with a keeper, and a flexible connection between the other end of the second member and the cap. 50 55

3. A self-draining oil can, comprising a container, a horizontal bottom member disposed above the base of the container to provide a housing between the base and the member, a second bottom member, disposed above the first-named member, defining a hollow, inverted cone, an auxiliary receptacle for oil extending through the first member and secured to and adapted to establish communication for oil with the second member, a detachable closure for the free end of the receptacle, and means for suspending the closure within the housing. 60 65

4. A self-draining can for viscous liquids, comprising a container, a mouth to the container for dispensing said liquids, a flared bottom member, disposed above the base of the container and converging into and communicating with a drainage receptacle, said receptacle being disposed within the base and adapted to catch the residue of oil remaining in the container after pouring the contents therefrom, and a detachable closure for the receptacle. 70 75
